UNITED STATES PATENT OFFICE.

CHARLES T. BRENNAN, OF WATERBURY, CONNECTICUT, ASSIGNOR TO THE E. J. MANNVILLE MACHINE COMPANY, OF WATERBURY, CONNECTICUT, A CORPORATION OF CONNECTICUT.

HEADING-MACHINE.

1,103,426.

Specification of Letters Patent. Patented Aug. 25, 1914.

Application filed April 18, 1914. Serial No. 832,893.

To all whom it may concern:

Be it known that I, CHARLES T. BRENNAN, a citizen of the United States, residing at Waterbury, in the county of New Haven and State of Connecticut, have invented a new and useful Improvement in Heading Machines, of which the following is a specification.

This invention relates to the mechanism which is provided for adjusting the punch holder of a metal heading machine. In double or triple stroke machines of this character the punches are mounted on a slide which is carried back and forth horizontally by a ram that is reciprocated by the crank shaft, and is moved up and down vertically in the front end of the horizontally movable ram by a connection from a cam on the driving shaft, so that on one forward movement of the horizontally movable ram one punch will operate on the stock held by the dies, and on the following movement forward of the ram another punch will operate on the stock.

The object of this invention is to provide a simple and convenient means by which the punch holder can be adjusted horizontally very finely so that the punches will accurately aline with the dies and properly act on the stock. In attaining this end the punch holder is mounted in a block that, when the means clamping the holder to the slide are loosened, can be moved sidewise in either direction in an opening in the slide by means of threaded wedge rods which pass up through the slide and are provided with nuts that are accessible from the top.

The invention is particularly adapted to and is shown and described herein as applied to a double stroke heading machine of the type set forth in United States Letters Patent No. 926,170, dated June 29, 1909.

Figure 1 of the accompanying drawings shows a vertical section of the horizontally movable ram, and a side elevation of the vertically movable slide carried thereby and the mechanisms for imparting a horizontal reciprocation to the former and a vertical reciprocation to the latter, of such a double stroke heading machine. Fig. 2 shows a plan of the punch ram and slide and the mechanisms for reciprocating these parts. Fig. 3 shows a front view of the vertically movable slide and the punch holder and punches carried thereby. Fig.

4 shows a side elevation of the same with a small part broken away to show how the punch holder is connected with the transversely movable block in the slide. Fig. 5 is an elevation of the vertically movable slide 60 with a portion cut in section in order to show the block in the slide which carries the stem of the punch holder and which is adjusted horizontally according to this invention.

In this type of machines the ram 1 is moved back and forth horizontally by means of a crank rod 2 that is thrown by the crank 3. The slide 4 is moved up and down in a guideway in the front end of the ram 70 by means of rocker arms 5 on a shaft 6 which has a rocker arm 7 that is thrown by the connecting bar 8 which is reciprocated by the cam 9 on the driving shaft 10, (Fig. 1). These mechanisms for imparting 75 a horizontal reciprocation to both the ram and slide and a vertical reciprocation to the slide are well known and are substantially the same as shown in the patent referred to.

The punches 11 and 12 are fastened in the 80 front face of the punch holding block 13 in any desired manner. Projecting from the back face of the punch holder is a stem 14. This stem extends into and fits an opening in a block 15 which is movable horizontally 85 on an opening 16 in the vertical slide. The side edges of this block, which holds the stem of the punch holder, are inclined and engaging these inclined edges are the inclined edges of rods 17 which extend from 90 the top down through the vertical slide into the opening containing the punch holder block. The upper ends of these wedge rods are threaded and provided with adjusting nuts 18 and clamping nuts 19. In order to 95 adjust the punch holding block horizontally to the correct position, the wedge rods are manipulated up and down by means of the nuts so that the block is wedged either one side or the other as desired to effect the result. For instance, if it is desired to move the block toward the left the nuts on the rod on the left are loosened so that the rod may drop down and the nuts on the rod on the right are tightened so as to draw up 105 that rod. After the block has been moved to the desired position by drawing up the rod on the right the nuts on the rod on the left are again tightened so as to clamp the adjusting block in the correct position.

After the holder carrying the punches has been correctly adjusted the holder is further fastened in place by clamping it to the slide by means of the nut 20 on the bolt 21, which 5 extends through an opening in the lower part of the punch holder which is slightly larger in diameter than the bolt, and by the nut 22 on the bolt 23 that extends through a hole, which is slightly larger in diameter 10 than the bolt, in the upper part of the punch holder. In order to allow this adjustment the holes through the punch holder are larger in diameter than the bolts, and, to prevent the punch holder from slipping out 15 of adjustment, by the reason of the looseness between the bolts and the walls of the holes which they pass through, at the upper end the punch holder is provided with two screws 24 which are set up against the bolt 23. 20 To adjust the punches horizontally the screws 24 and the nuts 22 and 20 are slightly loosened and then the holder is moved as necessary by manipulating the block which contains the holder stem, by turning the nuts 25 on the threaded wedge rods. After the horizontal adjustment is obtained in this manner the nuts 20 and 22 are tightened and then the screws 24 are turned up. This insures a 30 very exact adjustment of the punches and securely holds them in such manner that they will not get out of adjustment.

The invention claimed is:

1. The combination in a heading machine of a horizontally movable ram, a vertically movable slide carried by the ram, a block 25 movable horizontally in the slide, means for moving said block horizontally in the slide, a punch holder carried by said block, and a punch holder carried by said block, and

means for clamping the punch holder to the slide. 40

2. The combination in a heading machine of a horizontally movable ram, a vertically movable slide carried by the ram, a block with inclined edges movable horizontally in the slide, wedge rods and nuts carried by the 45 slide for adjusting said block horizontally, a punch holder carried by said block, and means for clamping the punch holder to the slide.

3. The combination in a heading machine 50 of a slide, a block movably carried by the slide, rods and nuts carried by the slide and adapted to adjust said block horizontally, a punch holder carried by said block, and means for clamping the punch holder to the 55 slide.

4. The combination in a heading machine of a slide, a block with inclined edges movable horizontally in the slide, rods with wedge surfaces engaging the inclined edges 60 of said block, nuts for adjusting said rods, a punch holder carried by said block, and means for clamping the punch holder to the slide.

5. The combination in a heading machine 65 of a horizontally movable ram, a vertically movable slide carried thereby, a punch holder movable horizontally on the face of the slide, a block movable in the slide for adjusting the punch holder horizontally, and 70 rods extending up through the slide for wedging said block horizontally.

CHARLES T. BRENNAN.
